UNITED STATES PATENT OFFICE

WALTER LOUIS KRAHL, OF MONTCLAIR, NEW JERSEY, ASSIGNOR TO ARCTURUS RADIO TUBE COMPANY, OF NEWARK, NEW JERSEY, A CORPORATION OF DELAWARE

METHOD OF TREATING TUBES

Application filed January 27, 1928. Serial No. 243,904.

This invention relates to vacuum tubes and especially to a method of treating the tube whereby more efficient operation is obtained.

In the manufacture of vacuum tubes and especially tubes using carbon filaments I have found that during the process of exhausting the tube, a thin film of material is deposited upon the inner surface of the envelope and also upon the elements and the stem or press of the tube, which film apparently comprises particles of carbon, nickel and other material thrown off from the elements during exhaustion. On the inside of the envelope such a film does no damage but at the stem adjacent the conductors and also at the glass bead used to support the upper ends of the elements the presence of this film causes a leakage between certain conductors which may result in poor operation of the tube, giving rise to howls, squeals and other noises detrimental to the operation of the tube.

The object of the invention, therefore, is to provide a method for breaking down this thin film of material and eliminating the danger of leakage between the conductors adjacent the glass.

The invention is illustrated in the accompanying drawing in which the single figure shows a vacuum tube connected in a circuit to perform the method of the invention.

The invention may be applicable to any form of vacuum tube but I have illustrated the vacuum tube shown and described in the application of Walter Louis Krahl entitled "Vacuum tube construction and circuit therefor", Serial No. 156,947, in which a glass envelope 10 is shown mounted in the usual base 11 supporting the terminals 12 for the elements. A stem or press 13 is provided into which the conductors 14 for supporting the elements are sealed and a glass bead 15 is sealed to several of the conductors at the upper end of the tube to form a means for insulating spacing the upper ends thereof.

During the process of exhausting the tube, a

film 16 is formed upon the stem adjacent the conductors and a film 17 also forms upon the glass bead 15. These films may often be substantially invisible to the naked eye but present a conducting path which permits current to leak between the various conductors.

In order to eliminate this danger of leakage between the conductors, I have found that the film may be burned off by introducing high tension current to the terminals of the tube. Accordingly, an ordinary spark coil 18 having a primary winding 19 connected to a source 20 of current supply has its secondary winding 21 connected to any two of the terminals of the tube. Upon the operation of the coil, high tension current is introduced into the tube through the terminals and sparks across the surface of the glass both at the stem 13 and at the bead 15 between the conductors, effectively removing the film therefrom. A few seconds is sufficient to completely remove the film and the tube may then be shifted so that another set of terminals are connected to the high tension leads when the current is again turned on.

It will be evident from the above that I have provided an extremely simple method of removing the conducting film deposited upon the glass insulation parts of the tube between the conductors which method is easy to carry out and greatly improves the tube so that the efficiency thereof is increased.

While I have explained the invention as adaptable to a treatment of a specific type of thermionic vacuum tubes, it is to be understood that the invention may be used in connection with any vacuum tubes in which a deleterious film may be formed in the course of construction or otherwise, between the conductors of the elements. I do not, therefore, desire to limit my invention except as defined in the appended claims.

Having thus described my invention, what I claim is:

1. The method of reducing leakage between conductors in a vacuum tube which comprises causing high tension current to flow between said conductors.
- 5 2. The method of reducing leakage between the conductors of a vacuum tube which comprises applying high tension current to two of said conductors and thereafter applying high tension current to the remaining conductors in pairs.

In testimony whereof, I affix my signature.

WALTER LOUIS KRAHL.
